G. Jassath

UNITED STATES PATENT OFFICE.

G. JASSATH, OF NEW YORK, N. Y.

IMPROVEMENT IN CARTRIDGE-BOXES.

Specification forming part of Letters Patent No. 33,306, dated September 17, 1861.

To all whom it may concern:

Be it known that I, G. JASSATH, of the city, county, and State of New York, have invented a new and Improved Cartridge-Box; and I do hereby declare that the following is a full, clear, and exact description of the same, reference being had to the annexed drawings, making a part of this specification, in which—

Figure 1 is a front view of my invention in an open state; Fig. 2, a transverse vertical section of the same in a closed state, x x , Fig. 1, indicating the plane of section.

Similar letters of reference indicate corresponding parts in the two figures.

The object of this invention is to construct the cartridge-box in such a manner that it may be readily filled with cartridges and the latter readily withdrawn from the box when desired for use.

The invention consists in having a box constructed of sheet metal or other proper material provided with a lid and inserted within a box of leather or other proper material, the first-mentioned box having a series of inclined tubes to receive the cartridges, as hereinafter fully described.

To enable those skilled in the art to fully understand and construct my invention, I will proceed to describe it.

A represents a box, which may be of sheet metal and of quadrilateral form, provided at its front or outer side with a lid B, which is hinged or jointed to the box at its upper end, as shown at a . The lid B extends down nearly the whole depth of the box, so that when the lid is opened the interior of the box will be nearly all exposed. The box A has a series of sheet-metal tubes b fitted within it in an inclined position, the outer ends of the

tubes b being considerably higher than the inner ends, as shown clearly in Fig. 2.

The tubes b are made of such diameter that they will receive the cartridges, the tubes being arranged in rows side by side, as shown in Fig. 1. By having the tubes b secured in the box A in an inclined position two important results are attained—to wit, the obtaining of tubes b of requisite length within a box A comparatively narrow or of moderate width, and the ready filling of the tubes with the cartridges and the withdrawal of the same from the tubes with facility either by the wearer or the one behind him in the ranks. When the lid B is raised, all the cartridges are fully exposed and very accessible.

The box A is inclosed within a box C, which may be of leather, having a flap c, which projects down in front of lid B and is secured to a button d at the bottom of box C. The box C is fitted to the wearer in the usual manner. The box A effectually protects the cartridges from dampness, while the leather box C protects the box A.

I do not claim, broadly, a cartridge-box constructed of two boxes, one being fitted within the other; but

I do claim as new and desire to secure by Letters Patent as an improved article of manufacture—

A cartridge-box formed of a box A, provided with a series of inclined tubes b and fitted within an outer or external box C, all arranged substantially as shown and described.

G. JASSATH.
